United States Patent Office

Des. 194,895
Patented Mar. 26, 1963

194,895

COMBINED NEWSPAPER BOX AND SUPPORT THEREFOR

Bela Bardos, 7604 Granada Drive, Fort Wayne, Ind.

Filed Mar. 29, 1962, Ser. No. 69,487

Term of patent 3½ years

(Cl. D74—9)

FIG. 1

FIG. 2

FIG. 3

FIG. 4

FIG. 5

FIG. 1 is a perspective view of a combined newspaper box and support therefor showing my new design;

FIG. 2 is a side view thereof;

FIG. 3 is a front view;

FIG. 4 is a top view; and

FIG. 5 is a sectional view thereof taken along the line 5-5 of FIG. 1.

I claim:

The ornamental design for a combined newspaper box and support therefor, as shown.
